UNITED STATES PATENT OFFICE.

WILLIAM A. BUCHANAN, OF ASHEVILLE, NORTH CAROLINA.

THILL-COUPING.

No. 796,185.

Specification of Letters Patent.

Patented Aug. 1, 1905.

Application filed January 23, 1905. Serial No. 242,394.

To all whom it may concern:

Be it known that I, WILLIAM A. BUCHANAN, a citizen of the United States, residing at Asheville, in the county of Buncombe and State of North Carolina, have invented a new and useful Thill-Coupling, of which the following is a specification.

This invention relates to thill-couplings, and has for its object to provide an improved device of this character wherein the parts are arranged to facilitate the coupling of the thills with the front axle and to prevent rattling thereof when the device is in use.

Another object of the invention is to provide for adjusting the tension of the antirattler spring, so as to accommodate the same to different conditions and to take up wear thereon.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a longitudinal sectional view of a thill-coupling embodying the features of the present invention. Fig. 2 is a detail perspective view of the clip plate or body of the coupler. Fig. 3 is a plan view thereof with parts broken away to show the oil-reservoir. Fig. 4 is a detail perspective view of the antirattler spring. Fig. 5 is a detail perspective view of the thill-iron.

Like characters of reference designate corresponding parts in each and every figure of the drawings.

The device of the present invention includes a body member or clip-plate 1, the forward end portion 2 of which is increased in thickness and projects below the rear portion of the body with its upper portion provided with a transverse substantially semicylindrical socket 3 intersecting opposite sides of the plate. The relatively thin portion of the plate or body is pierced by a pair of openings 4, and there is another opening 5 intersecting the rear portion of the enlarged front end of the plate. The part 2 of the body 1 constitutes the fixed jaw of the coupling, and upon the forward end of this fixed jaw there is a

movable jaw 6, hinged or pivoted to the top of the fixed jaw, as at 7, and overlapping the socket 3, the under side of the movable jaw being provided with a transverse socket or recess 8, designed to register with the socket or recess 3. The rear free extremity of the movable jaw 6 overlaps the opening 5 and is provided with a notch or bifurcation 9, which registers with said opening.

For the attachment of the body to an axle, a portion of which has been shown at 10 in Fig. 1 of the drawings, there is an ordinary axle-clip 11, embracing the axle, with its end portions passing through the openings 4 and clamped thereto by means of the nuts 12.

The thill-iron 13 is connected to the thill 14 by means of the usual T-headed bolt 15, the rear end of the iron being projected in rear of the thill and provided with a fork or yoke 16, having a cross-bar 17 extending between its extremities and designed to be received within the seat or socket 3 of the stationary jaw 2, the movable jaw 6 being received upwardly through the fork and over the cross-bar 17, so as to receive the latter in the seat or recess 8.

To hold the movable jaw 6 down upon the cross-bar 17 of the fork of the thill-iron, there is provided a latching device consisting of a bolt 18, having its upper end provided with a cross-head 19 and its lower end threaded for the reception of a nut 20, which is provided at diametrically opposite sides with trunnions or pivot projections 21, there being a substantially U-shaped spring 22, having its lower side shorter than its upper side and provided with a slot or bifurcation 23 to receive the nut 20, the sides of the bifurcated portion being bent to form bearing-eyes 24, receiving the trunnions 21, whereby the spring is hinged or pivoted to the nut and is capable of being swung vertically thereon. The free end of the upper side of the spring is provided with a longitudinal bifurcation 25, and the extremities 26 of the sides or fork members formed by the bifurcation are bowed inwardly or toward the lower side of the spring, so as to form cam-terminals.

In assembling the latch device upon the body of the coupler the nut 20 is removed from the bolt 18, and the latter is then thrust downwardly through the opening 5, with its stem portion lying in the bifurcated free terminal 9 of the movable jaw 6, the head of the bolt lying across the top of the movable jaw. The nut 20 is then fitted to the lower end of

the stem, with the spring in a vertical position, as indicated by the dotted lines in Fig. 1, the spring being turned or rotated so as to work the nut upwardly upon the bolt until the cam-terminals 26 of the free side of the spring engage the under side of the body, and then the lower end of the spring is forced rearwardly upon the trunnions 21 as an axis until the spring snaps into the position indicated in full lines flat against the under side of the coupling, wherefore the movable jaw 6 will be effectually locked, so as to prevent displacement of the thill-iron from the coupling members. It will here be explained that the body or plate member 1 is somewhat thinner than the fixed jaw portion 2 in order that the lower faces of the nuts 12 may lie substantially flush with the under side of the fixed jaw in order that the upper side of the spring may lie flush against the bottom faces of the nuts and the lower face of the fixed jaw. Although the extremities 26 of the upper side of the spring have been shown in engagement with the forward nut 12 and have been described as bearing against the under face of the fixed jaw, it will be understood that the effect is the same, and whether or not the free end of the spring bears against the under side of the fixed jaw will depend entirely upon the distance between the opening 5 and the adjacent opening 4. The thill-iron may be readily released by forcing the spring downwardly to the dotted-line position in Fig. 1, whereupon the nut may work downwardly sufficient to permit of the headed bolt 18 being elevated and tilted rearwardly to clear the free end of the movable jaw, and thereby permit of the latter being swung open upon its hinge or pivot 7 to release the thill-iron. It will here be noted that the opening 5 for the bolt 18 is inclined upwardly and rearwardly to a slight extent and is somewhat wider than the bolt in order that the latter may be tilted rearwardly to clear the free end of the movable jaw, the spring 22 of course bringing the bolt into a substantially upright position into snug engagement with opposite sides of the opening 5 at the top and bottom thereof to hold the same rigidly in place and prevent looseness thereof.

In the rear face of the socket 3 there is a chamber 27, which is cut through the fixed jaw from side to side thereof and in which suitable packing or absorbent material 28 is fitted, each end of the chamber being closed by a plug 29 to retain the absorbent material in place. This absorbent material is designed to be saturated with oil, so as to maintain the bearing between the thill-iron and the two jaws of the coupling in the properly-lubricated condition, thereby to permit of an easy working of the thill-irons under the up and down movements imparted thereto by the draft-animal.

From the foregoing description it will be

understood that the device of the present invention is entirely complete in itself and may be applied to any ordinary vehicle axle and thill without altering or changing the same in any manner whatsoever. When fitted in place, the thill may be readily detached and disconnected in a very simple and expeditious manner. Moreover, rattling of the parts of the coupling is effectually prevented, and the tension of the spring may be conveniently adjusted by means of the nut 20 to take up wear, and thereby insure a proper fit of the movable jaw, the bolt 18, and the spring.

Having fully described the invention, what is claimed is—

1. A thill-coupling comprising a fixed jaw, a movable jaw, an endwise-movable link connecting the movable jaw and the fixed jaw, and a substantially U-shaped antirattling spring carried solely by and hinged to the link and capable of being turned upon its pivotal support into engagement with one of the jaws in the manner of a cam to place a spring tension upon the link and the movable jaw.

2. A thill-coupling comprising a fixed jaw, a movable jaw hinged thereon, an endwise-movable link piercing the two jaws, and a substantially U-shaped antirattling spring carried solely by and hinged to the lower end of the link and capable of being turned upon its hinged support into engagement with the under side of the fixed jaw to place a spring tension upon the link and the movable jaw.

3. A thill-coupling comprising a fixed jaw having a vertical opening, a movable jaw hinged upon the fixed jaw with its rear free end provided with a bifurcation which is in alinement with the opening of the fixed jaw in the closed position of the pivotal jaw, a headed link movable endwise in the opening in the bifurcation with its head extending across the top of the pivotal jaw, and a substantially U-shaped antirattling spring carried solely by the lower end of the link with one terminal hinged to the link and capable of being swung upwardly thereon to bring the opposite side of the spring into engagement with the bottom of the fixed jaw to place a spring tension upon the link and the pivotal jaw.

4. A thill-coupling comprising a fixed jaw, a movable jaw, an endwise-movable link connecting the jaws, and a substantially U-shaped antirattling spring having one end hinged to the link and adjustable longitudinally thereon, said spring capable of being turned upon its hinged support into engagement with one of the jaws to place a spring tension upon the link and the movable jaw.

5. A thill-coupling comprising a fixed jaw, a movable jaw, an endwise-movable link connecting the jaws and provided with a threaded portion, a nut adjustable upon the threaded portion of the link, and a substantially U-shaped antirattling spring having one termi-

nal hinged upon the nut and capable of being swung thereon to bring its opposite side into engagement with one of the jaws to place a spring tension upon the link and the movable jaw.

6. A thill-coupling comprising a fixed jaw having an opening, a movable jaw hinged upon the fixed jaw and provided with an opening which is in alinement with the opening of the fixed jaw when the movable jaw is closed, a headed link received within the two openings with its head lying across the outer side of the movable jaw and its opposite end being threaded and projected beyond the fixed jaw, a nut adjustable upon the threaded portion of the link and provided with opposite trunnions, and a substantially U-shaped spring having one end bifurcated to receive the nut and hinged to the trunnions thereof, the opposite end of the spring being bifurcated to straddle the link when turned into engagement with the fixed jaw.

7. A thill-coupling comprising a body pierced by upright openings and terminating at its forward end in a thickened fixed jaw projected below the bottom of the body and provided with an upright opening, an axle-

clip to engage the openings of the body and connect the same to an axle, a movable jaw hinged at its forward end to the fixed jaw with its rear free end bifurcated, a substantially T-shaped link received within the bifurcation of the movable jaw and the opening of the fixed jaw with the head of the link lying across the top of the movable jaw, the lower portion of the link being threaded and projected below the fixed jaw, a nut adjustable upon the threaded portion of the link and provided with opposite trunnions, and a substantially U-shaped spring having its lower side shorter than its upper side and bifurcated to receive the nut to which the spring is pivotally connected, the opposite side of the spring being projected beyond the lower side and bifurcated to receive the link when the spring is swung up into engagement with the under side of the fixed jaw.

In testimony that I claim the foregoing as my own I have hereto affixed my signature in the presence of two witnesses.

WILLIAM A. BUCHANAN.
